TRANSPORTING EQUIPMENT FOR MOLTEN METAL

Edward H. Whittaker, Jersey City, N. J.

Original application July 9, 1941, Serial No. 401,651. Divided and this application May 20, 1942, Serial No. 443,794

3 Claims. (CL 22—82)

This invention relates to transporting equipment for molten metal used in foundry plants, and this application is a division of an application for United States patent on Foundry plants, filed by me July 9, 1941, Serial Number 401,651.

The principal objects of the invention are to provide equipment which may be manufactured at a low cost but which is comparatively safe in use, and equipment including ladles which may be compactly stored and transported when not being used for filling molds, and detachable balls and operating or guiding handles which may be placed in operative relation to the ladles when their use is required. Thus a ladle may receive molten metal at the melting furnace and be moved on a conveyor in rather restricted quarters, and equipped with a bail and guiding handle means at or adjacent the pouring station for lifting and guiding the ladle to a position over the sprue holes or gates of the mold.

Other objects and advantages of the invention will appear in the following detailed description, taken in connection with the accompanying drawing, forming a part of this specification, and in which drawing—

Figure 1 is a side elevation of transporting equipment constructed according to the present invention, a part being broken away and shown in section to illustrate details.

Figure 2 is an end elevation of the same.

Figure 3 is a plan of the detachable handle or guiding means.

Figure 4 is a side elevation of an eye part of the bail.

Figure 5 is a vertical section on the line 5—5 of Figure 4.

Figure 6 is a side elevation of a bar forming a part of the bail.

Figure 7 is a side elevation of an arm of the bail.

Figure 8 is an end elevation of the arm.

The equipment comprises a ladle 9, a bail 10 and handle means 11 detachable with respect thereto, and means 12 for releasably holding the handle means on the ladle.

The ladle is preferably, altho not necessarily, of the type shown in my co-pending application for United States patent filed May 20, 1942, Serial Number 443,795, which is adapted to permit the molten metal to flow from the bottom of the ladle. It includes an inverted frusto-conical wall portion 13 and diametrically disposed laterally extending trunnions 14 each having a reduced portion 15 intermediate its ends, provid-

ing a body part 16 and a head 17. These trunnions have a dual purpose—to cooperate with the detachable ball and to support the means 12, as shown in Figures 1 and 2.

5 The ball is preferably made mainly of stock or easily procurable material such as a ring 18, horizontal bars 19, bolts 20 having nuts 21, and bolts 22 having nuts 23. The ring 18 has a segmental spacer 24 welded to it, as shown in Figures 4 and 5, to fill approximately two-thirds of the opening of the ring, leaving an eye 25 above the spacer for a hook 26 of hoist mechanism, not shown in the drawing. To accommodate the shanks of bolts 20, used to secure the ring 18 and spacer 24 to the central portions of the bars 19, the bars are provided with transverse openings 27 and the spacer 24 with transverse openings 28. This assembly constitutes a yoke 29 to the end portions of which are pivotally connected arms 30, preferably arcuate in shape, so they may be swung into position and connected to the trunnions 14, or folded inwardly beneath the ring 18 to render the ball compact when being stored or transported. Each arm is preferably made to comprise a body part 31 and a lower terminal portion 32. The body part is preferably of channel shape comprising a web 33 and flanges 34. The upper ends of the flanges are provided with aligned openings 35 for the shanks of bolts 22, which latter are accommodated in aligned openings 36 in the end portions of bars 19. Each terminal portion 32 has a key-hole slot 37, the upper portion 38 of which is of a size to freely receive the head 17 and the lower restricted portion 39 to snugly receive the reduced portion 15 of its respective trunnion 14.

40 Referring now to the handle means 11, it comprises a ring 40 made to snugly engage the tapered wall 13 of the ladle, and diametrically disposed lateral arms 41 extending therefrom, provided with hand grip portions 42. The ring 40 is preferably of inverted frusto-conical shape, the inner taper 43 corresponding to the taper of wall portion 13 somewhat spaced below the trunnions 14 and above the bottom of the ladle, so as to have surface to surface contact with the ladle when the ring is raised into contact with same and so as to fit in a horizontal position symmetrically with respect to the axis of the ladle.

45 The means 12 in the example shown comprises lengths of chains 44 preferably having rings or handles 45 at their end portions, the other ends being secured as at 46 to the trunnions 14. When the handle means 11 is in place on the

ladle, intermediate portions of the chains may be quickly wrapped around the arms 41 to hold the handle means 11 in place.

As an example of use of the transporting equipment for molten metal, the ladles with the balls and handle means detached, may be charged at the melting furnace and moved on any suitable conveyor to the pouring station, where they may be equipped with bails 10, lifted and handle means 11 applied. At the pouring station they may be used to assist in placing the ladles over the molds, and when empty, the balls and handle means may be detached and the ladles returned to the melting furnace on a conveyor to be recharged, or to storage space if no longer needed for that particular casting operation.

I claim:

1. In transporting equipment for molten metal, the combination of a ladle provided with oppositely extending, laterally disposed trunnions, and handle means below said trunnions, detachably carried by the ladle, including a body portion embracing the wall of the ladle, oppositely extending laterally disposed arms on said body provided with enlarged hand grip portions at their free ends, and flexible members carried by said trunnions with the intermediate portions thereof adapted to be wrapped around said arms between said body portions and hand grip portions, to hold said body in embracing relation to the ladle with the free ends of said flexible members depending from said arms.

2. In transporting equipment for molten metal, the combination of a ladle provided with oppositely extending, laterally disposed trunnions, and a detachable bail for the ladle including a yoke comprising a pair of paralleling bars, a spacer between with the intermediate portions of said bars, provided with a segmental portion, a ring, of less thickness than said spacer, extending about the periphery of the segmental portion of said spacer and above said spacer, and means securing said bars to said spacer, said bail also including a pair of arms, depending from opposite ends of said bars, provided with means at their lower ends for detachable connection with said trunnions.

3. In transporting equipment for molten metal, the combination of a ladle provided with oppositely extending, laterally disposed trunnions; a bail for the ladle pivotally connected to said trunnions; handle means including a body portion detachably embracing the wall of the ladle below said trunnions, and oppositely extending, laterally disposed arms carried by said body portion, said arms located one below each of said trunnions; and means detachably suspending said handle means from said trunnions, including a chain for each companion trunnion and arm, each chain having its upper end portion secured to its respective trunnion and its intermediate portion wrapped about its respective arm, with a free end portion of the chain depending from its respective arm.

EDWARD H. WHITTAKER.
